P. Quinn,
Boiler-Tube Stopper.

No 65,603.

Patented June 11, 1867.

United States Patent Office.

PATRICK QUINN, OF SOUTH NEW MARKET, NEW HAMPSHIRE.

Letters Patent No. 65,603, dated June 11, 1867.

IMPROVED FERRULE FOR STOPPING LEAKS IN BOILER-TUBES.

The Schedule referred to in these Letters Patent and making part of the same.

TO ALL PERSONS TO WHOM THESE PRESENTS SHALL COME:

Re it known that I, PATRICK QUINN, of South New Market, in the county of Rockingham, and State of New Hampshire, have invented an Improved Device for Arresting or Preventing a Leak in a Boiler-Tube; and I do hereby declare the same to be fully described in the following specification and represented in the accompanying drawings, of which—

Figure 1 is a side view of one form of it, viz; that which is intended for use when the leak is close to the end of a tube, or near its junction with the end plate of a boiler.

Figure 2 is a side view of another form of the invention, or that calculated for use when the leak to be stopped is near the middle, or between the same and the end of the tube.

Figures 3 and 4 are axial and longitudinal sections of such forms, exhibiting their applications to tubes.

Figures 5 and 6 are end views of the first, and

Figure 7 is an end view of the second form, each of such forms containing the principle of my invention.

This invention may be said to be an improvement on that patented in Letters Patent of the United States numbered 39,717, dated September 1, 1863, the invention covered by such patent consisting of a tapering spring gland and a tapering thimble, arranged one on the other, a separate screw-bolt, washer, and nut being employed to force one into the other so as to cause the entering one to expand the other. These devices for drawing the gland upon the expanding tube by being separate from the said gland and tube, are liable to be lost or mislaid, and as the gland and tube cannot be applied to good advantage or without risk or danger of injury to the tube without such contrivances, I have made a tapering gland and tube with screws cut on them so as to be part of them, such tube being provided with a key orifice for receiving a key by which the tube may be revolved to expand the gland. I term the part to be expanded the gland. I do not, however, split it throughout its length, but only a part thereof, as when split throughout its length it is liable to leak steam through the opening.

In the drawings, A denotes the gland, and B the expander; C the boiler tube to be expanded, and D the boiler-plate in which the tube C is fixed. In fig. 1 the gland is represented as provided with a flange or head, a, extending from its outer end, such flange being to support the gland against the plate D and make a close joint therewith. In figs. 2 and 4 the gland is a simple tube without such flange at either end, it having two of the expanders arranged and screwed into it. The gland should have a diameter corresponding with that of the bore of the tube to which it is to be applied. The expander is to be a short tube formed conical or tapering on its external surface, and with a prismatic bore, such bore being shown at b. This prismatic bore constitutes an orifice for receiving a key for revolving the expander. A male screw, c, is cut on the outer surface of the expander, and is to enter a corresponding female screw, d, made within the gland. If preferable, the opening in the gland for receiving the female screw may be tapering, but it will suffice to make either or both the screws tapering in such manner that when the expander is in the act of being screwed into the gland the latter shall be expanded by the former and against the tube C.

In using my invention the gland, with the expander or expanders moved a short distance within it, is to be introduced into the pipe so as to cover and extend by in opposite directions the opening from which the leak may proceed, after which a key should be introduced into the expander and revolved so as to cause it to revolve and screw into the gland and expand the latter at its end in which the gland may be, so as to cause the gland at such end to fit closely or steam-tight to the tube. Thus, when the gland is introduced within the boiler tube, it will seal the opening thereof through which the leak may take place.

I make no claim to the invention described in the patent hereinbefore mentioned. What I claim as my invention, is—

The gland and the expander, as made, not only with the male and female screws, and with either or both tapering, as specified, but as having a key-hole formed in the bore of the expander, as set forth.

PATRICK QUINN,
